(57) **CLAIM**

The ornamental design for rear marker light bar, as shown and described.

DESCRIPTION

FIG. 1 is a view from above, rear and left side;
FIG. 2 is a rear view, with the front view being devoid of surface ornamentation;
FIG. 3 is a top view, with the bottom being generally flat and devoid of surface ornamentation; and,
FIG. 4 is a view from the left side, with the right side being a mirror image.

The broken line showing of the vehicle is for illustrative purposes only and forms no part of the claimed design.
